UNITED STATES PATENT OFFICE.

ALBERT ENGELGAU, OF BURKE, SOUTH DAKOTA.

MEANS FOR RECORDING AND GAUGING THE IRREGULARITIES OF RAILWAY-TRACK RAILS.

Application filed October 10, 1923. Serial No. 667,692.

This invention relates to a combination gauge and recorder for installation upon a work or inspection car whereby the irregularities of railway track rails may be properly gauged and recorded during the movement of the car over the track for consequently allowing the rails to be set to the proper gauge with respect to each other.

The primary object of my invention resides in the provision of such a means whereby track rails may be properly gauged and the result recorded in a novel, simple and expeditious manner and this without requiring any great skill on the part of the workmen.

A still further object is to provide such a means wherein an alarm is sounded in the event that the irregularities between the parallel rails of a trackway exceed a certain predetermined degree for thereby signalling the workmen upon the car that that particular point in the trackway must be set to a proper gauge before proceeding further.

Briefly described, my novel track rail gauging and recording mechanism comprises a telescopic axle that is employed in lieu of one of the usual axles of the work or inspection car and upon the opposite ends of which are horizontally and vertically pivoted rail engaging wheels, means being provided for normally displacing the sections of the axle outwardly with respect to each other and for consequently maintaining the said wheels in close engagement with the rails. Upon one of the axle sections is disposed a slowly moving record sheet upon which a record is made of the irregularities between the parallel rails of the trackway and this through the medium of a marker that is operatively connected to the other section of the axle, it being of course apparent that inward and outward movements of the axle sections with respect to each other, caused by the irregularities of the rails will control the operation of the recording mechanism, the result thereof being always visible to the workmen upon a car.

A still further object of the invention is to provide such a mechanism wherein the wheels upon the opposite ends of the axle may be swung upon both their horizontal and vertical pivots for so positioning the same with respect to the rails as to have

the flanges thereof closely hug the inner edges of the rail treads and this at a point slightly rearwardly of the vertical axes of the wheels for consequently precluding any possibility of the car hopping the tracks, means being provided for securely locking the wheels in their adjusted positions for preventing any pivotal movement of the same upon the ends of the axle when the mechanism is functioning.

With the above and other objects in view as the nature of the invention will be better understood, the same comprises the novel form, combination and arrangement of parts hereinafter more fully described, shown in the accompanying drawings and claimed.

In the drawings wherein like reference characters indicate corresponding parts throughout the several views,

Figure 1 is a front elevational view of my track rail gauging and recording mechanism per se,

Figure 2 is a top plan view thereof,

Figure 3 is an enlarged detail longitudinal sectional view through the recording mechanism per se,

Figure 4 is a horizontal sectional view thereof taken approximately upon the line 4-4 of Figure 3, for disclosing the mechanism of this recording means more clearly,

Figure 5 is a vertical section through this recording mechanism and taken substantially upon the line 5-5 of said Figure 3,

Figure 6 is an enlarged fragmentary sectional view through a portion of the telescopic car axle for disclosing more clearly the circuit making and breaking mechanism for the alarm device,

Figure 7 is an enlarged fragmentary longitudinal section through one end of this telescopic axle for more clearly disclosing the specific mounting means for the rail engaging wheels, it being understood in this connection that the wheels upon the opposite ends of said telescopic axle are similarly connected thereto,

Figures 8, 9, 10 and 11, are enlarged perspectives of the specific elements employed in horizontally and vertically pivoting the track engaging wheels to the opposite ends of said telescopic axle, and

Fig. 7^a is a detail view showing, in elevation the structure also seen in Fig. 7, the view being in top plan.

In the prelude to this specification I have stated that the telescopic axle may be employed in lieu of one of the usual axles of the work or inspection car upon which this present device is installed, however, the device may be entirely separate from the car and secured to the rear axle or frame thereof through the medium of suitable connecting bars 5-5 in Figure 2.

10 My invention per se embodies the provision of a telescopic axle 6 that includes an outer hollow section 7 and an inner solid section 8 that are normally displaced outwardly with respect to each other through the medium of springs 9 upon opposite sides of said axle and being connected at one end to laterally extending pins 10 formed upon the inner end of the solid axle section 8 and that have free sliding movement within 15 longitudinal slots 11 in said tubular section 7, the opposite ends of these springs being secured to relatively elongated eye-bolts 12 that are adjustably secured through the medium of jamb nuts 13 to laterally extending 20 ears 14 formed upon said hollow axle section 7, whereby the tension of said spring may be increased or diminished as desired.

The outermost end of each axle section is bifurcated as at 15 in Figure 9 and within 25 which is set one curved end of a connecting block 16, Figure 8, and secured thereto through the medium of a horizontal pivot 17 that extends through registering openings in the legs of the bifurcations and said 30 curved end of the connecting block 16. The opposite end of said connecting block 16 is curved in an opposite direction from its inner end and over which is positioned a yoke 17^a, Figure 10, the upper and lower 35 arms of said yoke being formed with aligned openings that register with a vertical bore 18, Figure 8, in the adjacent end of said connecting block, whereby the elements are pivotally secured together through the medium of a vertical pivot 19. The yokes are 40 formed with pintles 20 upon which are journaled the track rail engaging wheels 21 and 22, each of these pintles being reduced and screw-threaded at its outer end whereby the 45 respective wheel may be secured thereto through the medium of a jamb nut 23, Figure 7.

Each of the axle sections adjacent its bifurcated end is formed with two pairs of 50 radially extending equally spaced arms 24 and 24^a respectively, the ends of the first named of which are bifurcated at 25 and within which are pivotally mounted blocks 26. Positioned slidably within the bores 55 of the blocks 26 carried by the vertically extending pair of arms 24 are the screw-threaded ends of relatively elongated eye-bolts 27 the opposite eyed ends thereof being pivotally disposed as at 28 within the bifurcated ends 29 of arms 30 that extend in

a vertical direction and that are formed upon upper and lower sides of the before mentioned connecting block 16 and adjacent its horizontally pivoted end, Figure 8.

Each of the before mentioned yokes 17^a is formed upon opposite sides with outwardly and slightly inwardly curved arms 31 the ends of which are bifurcated at 32 and within which are pivotally disposed the inner eyed ends 33 of an additional pair of eye-bolts 34 that are slightly longer than the before mentioned eye-bolts 27. The screw-threaded ends of these eye-bolts 34 also extend within the ball joints 26^a carried by the horizontally extending ones of the before mentioned arms 24^a of the axle sections. Here, I would direct attention to the fact that the screw-threaded ends of the eye-bolts 34 are connected, as shown in Figure 11, to the outer ends of the arms 24^a through 85 the medium of what may be designated as ball joints 26^a. A conventional type of a joint is shown here and permits the necessary pivotal action essential in permitting proper relative angling of these bolts with 90 respect to the bolts 27 when the wheel is angled upon horizontal and vertical planes. Threaded upon the eye-bolts 27 and 34 at opposite sides of the pivotal connections 26 and 26^a are jamb nuts 35 for securely 95 fastening said eye-bolts to the arms 24 after the rail engaging wheels 21 and 22 have been adjusted to the desired angle for consequently preventing any pivotal movements of the same when the device is in use.

In actual practice it is preferable that these wheels 21 and 22 be swung inwardly upon their horizontal pivots at their upper ends for positioning the same at an angle of substantially 20 degrees, these wheels being also moved upon their vertical pivots in a direction inwardly at their front ends for consequently positioning the flanges 27 thereof in close engagement with the inner edges of the rail treads and this at a point slightly 110 rearwardly of their vertical axes as clearly shown in Figure 1, for thereby causing a tendency of the wheels when going forward to press down more than their natural weight on the rails.

Fixed upon the top side of the outer tubular section 7 of the telescopic axle 6 is a record sheet carrying casing 36 within which is journaled a horizontal roller carrying shaft 37 adjacent the front end thereof and upon which is disposed a record sheet 38 in roll form, this record sheet being relatively wide and having a pair of spaced parallel extending lines 39 upon the top surface thereof representative of the rails of the trackway and within which are mileage indications 40. This record sheet 38 extends upwardly from the roll and passes between a fixed and movable guide roller 41 and 42 respectively. The fixed 120 125 130

guide roller 41 is journaled within the casing adjacent the upper front corner thereof while said movable roller 42 is provided at its opposite ends with pintles 43 that are positioned beneath the front fingered ends of a pair of pull strips 44 that are formed at their rear ends with pendant lugs 45 and through which are openings for receiving guide rods 46. These guide rods 46 are carried by spaced brackets 47 upon the opposite side walls of the before mentioned casing 36 and are formed at their front ends with block bearings 48 into engagement with which is forced the pintles 43 of said movable roller 42 through the medium of coiled springs 49 encircling said rod between the lugs 45 of the pull strips 44 and abutments 50 upon said rod.

The sheet is then extended rearwardly horizontally and passed over a supporting strip 51 and thence beneath a rubber covered guide roller 52 and then over a relatively higher disposed and spaced guide roll 53 for so positioning the record sheet between these two rolls 52 and 53 whereby the markings thereon may be clearly viewed through a transparent cover 54 that is fitted within an opening in said casing 36.

This record sheet 38 is then brought downwardly and passed between a feed roll 55 and a spring tensioned roll 56 this feed roll 55 adapted to be extremely slowly rotated through the movement of the car over the rails for consequently unwinding the record sheet from its roll and passing the same into a compartment 57 provided at the rear end of said casing 36.

The feed roll 55 is rotated in the direction of the arrow, Figure 3, in an extremely slow manner through the medium of a train of speed reduction gearings appropriately arranged within the casing and designated generally 57. This train of gearing is operatively connected to one end of a flexible shaft 58 that extends outwardly of the casing and is equipped at its opposite end with a spur gear 59, Figure 7, that has mesh with a spur gear 60 arranged upon the hub of the rail engaging wheel 21 for rotation therewith.

At a point within the tubular section 7 of the telescopic axle 6 the solid section 8 is formed with a vertical arm 61 that has sliding movement within a longitudinal slot 62 formed in the top side of said hollow section 7. Connected at one end to this arm 61 as at 63 is one end of a rod 64 that extends parallel with said axle and engages within an opening in the adjacent side wall of the before mentioned record sheet carrying casing 36 and is pivotally connected at its opposite end as at 65 to the lower end of a rock bar 66 which rock bar is pivoted intermediate its ends to a bracket 67 within said casing. This rock bar 66 extends up-

wardly beyond the record sheet roll and is pivoted at its upper end as at 68 to an inwardly extending arm 69 that is in turn pivoted at its opposite end to one end of another arm 70 that extends horizontally within the casing above the record sheet 38 and is pivoted intermediate its ends to the top wall of the casing as at 71, the front end of this arm being equipped with a suitable form of marker 72 of Figure 3 that contacts with the record sheet between the parallel spaced lines 39 upon the top side thereof and at a point where this record sheet moves over the before mentioned guide strip 51 that in reality effects a table for said marker.

It will thus be seen that when the wheels have been properly set and preferably in a manner as shown in Figures 1 and 2 and the car moved over the rails the record sheet will be unwound from its roll and consequently drawn beneath the marker 72 and any irregularities in the track rails will occasion the displacement of the axle sections inwardly and outwardly of each other which displacement of the axle sections will control a movement of the record sheet carrying casing as well as the marker 72 for thereby recording these variations upon the record sheet whereby these rails may be set to the proper gauge.

The before mentioned vertical arm 61 that has sliding movement through the slot 62 of the tubular axle section 7 and that is formed upon said solid section 8 is equipped with an electrical contact finger 72 of Figure 6 that has movement beneath an inverted relatively U-shaped bracket 73 that is formed upon the upper end of an arm 74 which arm is connected to and insulated from said hollow axle section 7. The legs of this U-bracket 73 carry adjustable electrical contacts 75 that are engaged by said contact finger 72 whenever the irregularities of the track rails become relatively great for thereby completing an electrical circuit to a sounding device 76 which is preferably an electric horn. As a source of electrical supply a storage battery 77 is provided that is suitably supported upon the hollow axle section one terminal thereof being electrically connected to the axle while the other terminal is electrically connected to one contact of said sounding device 76 the opposite contact of this sounding device being electrically connected to a terminal post 78 upon said inverted U-shaped bracket 73.

The innermost end of the axle section 7 has pivoted thereto a bell crank lever 79 the lower arm of which is formed with a pair of spaced fingers 80 for engagement over a laterally extended pin 81 formed upon the solid axle section 8 whenever it is desired to prevent relative displacement of the sections with respect to each other such as when

passing over the frogs of switches for consequently preventing the wheels from climbing frogs and derailing, and the marker from moving from a straight path directly 5 centrally between the parallel lines 39 of the before mentioned record sheet 38. The opposite arm of this bell crank is equipped with a ~~as~~ 82 for co-operation with a toothed segment 83 carried by the tubular 10 axle section 7 for maintaining said bell crank in set position.

From the foregoing description when considered in conjunction with the accompanying drawings, it will at once be appreciated 15 by those skilled in the art, that I have provided a highly novel and operable means for gauging and recording irregularities of railway track rails, and even though I have herein set forth that this device consists of 20 certain specified structural elements it is nevertheless to be understood that departures may be had therein without affecting the spirit and scope of the appended claims.

Having thus described my invention, what 25 I claim as new and desire to secure by Letters Patent is:—

1. In a device of the class described, an extensible axle, wheels at the ends of said axle, and means between said axle ends and 30 wheels permitting said wheels to be moved on both vertical and horizontal axes and additional means for positively holding said wheels in set position.

2. In a device of the class described, an extensible axle, rail engaging wheels at the 35 ends of said axle, means interposed between the axle ends and said wheels for permitting the wheels to be adjusted simultaneously on horizontal and vertical axes, said means 40 comprising a block pivotally connected to said axle on a horizontal axis, and a yoke connected to said wheel and pivotally connected to said block by a vertical pivot, and additional means for positively maintaining 45 said wheels in set positions.

3. In a structure of the class described, an extensible axle bifurcated at one end, a block pivotally mounted between said furcations

upon a horizontal axis, a plurality of arms radiating from said block and from said 50 axle ends, a plurality of adjusting and retaining bolts pivotally connected with the block arms and adjustably and pivotally connected with the arms on said axle, and a rail engaging wheel pivoted upon a vertical 55 axis to said block.

4. In a device of the class described, an extensible axle, one of the sections of which is bifurcated at one end, a block arranged between the furcations, a horizontal pivot 60 pin passing through said furcations and block for permitting movement of the block in a vertical plane, a plurality of arms radiating from said block, a plurality of additional arms radiating from said axle end, all 65 of said arms being circumferentially spaced apart and being arranged in longitudinally aligned pairs, retaining bolts pivotally connected with the block arms at one end and adjustably and pivotally connected with the 70 axle arms at their opposite ends, a rail engaging wheel, a mounting therefor including a yoke, the arms of which straddle the aforesaid block, a vertical pivot pin connecting said yoke arms with said block, whereby 75 to permit said wheel to be adjusted on vertical and horizontal axes and to be held in set position.

5. In a device of the class described, an axle composed of telescopically connected 80 sections normally forced outwardly from each other by yieldable means, at least one of said sections being bifurcated at the outer end, a block arranged between the furcations and pivotally connected thereto by a 85 horizontally disposed pivot pin, a yoke pivotally connected to said block by a vertical pivot pin, said yoke carrying a journal, a wheel mounted upon said journal, a bearing equipped bracket carried by said yoke, a gear carried by said wheel, a pinion in mesh with said gear, and a shaft carried by said pinion and rotatably mounted in said bearing.

In testimony whereof I affix my signature.
ALBERT ENGELGAU,
